[57] **CLAIM**

The ornamental design for a portion of a shoe outsole, as shown and described.

DESCRIPTION

FIG. 1 is a plan view of a portion of a shoe outsole showing my new design;

FIG. 2 is a frontal perspective view thereof; and,

FIG. 3 is a rear perspective view thereof.

The broken line showing of the remainder of the shoe is for illustrative purposes only and forms no part of the claimed design.

FIG. 3

UNITED STATES PATENT AND TRADEMARK OFFICE
CERTIFICATE OF CORRECTION

PATENT NO. : Des 433,214
DATED : November 7, 2000
INVENTOR(S) : Sean M. McDowell

Page 1 of 4

It is certified that error appears in the above-identified patent and that said Letters Patent is hereby corrected as shown below:

Title page.

The title page, showing the illustrative figure should be deleted and substitute therefore the attached Title page.

Drawings.

Delete Drawing sheets 1-2, and substitute therefore the Drawing Sheets, consisting of Figs. 1-2, as shown on the attached pages.

Signed and Sealed this

Twenty-eighth Day of May, 2002
